Jos. C. Gentry

to Joseph C. Gentry, Philadelphia Pennsylvania
Sellers Patent. Dated Dec. 14. 1830.

The Schedule referred to in the Letter Patent and making part of the same containing a description in the words of the said Joseph C. Gentry himself of his improvement being a new machine for conveying animal power to any kind of machinery

Be it known, that I Joseph C. Gentry of Philadelphia, County of Philadelphia and State of Pennsylvania, have made an improvement being a portable machine for conveying animal power to my kind of machinery which is described as follows.

This machine consists of the following principal parts. 1. The Frame; 2. The Strap Wheel; 3. The Log Wheel. 1st The Frame is constructed in the following manner: make two rolls of timber about 4 inches square, placed at right angles and creping in the center. Into these rolls are tenoned four posts about 6 inches from the end of each roll to leave room for the screws for fastening them. They may be about 2 feet 6 inches high and 11 inches square. On the top are two other pieces of timber about 3 feet long and similar to the rolls, a opening each other at right angles in the center and tenoned into the posts. Another piece of timber on each of the same dimensions as the last mentioned is placed about 6 inches from the roll and tenoned into two other posts.

2. The Strap Wheel is made of iron or any suitable material about 8 feet diameter and 3 inches thick. On the periphery is a groove or any other suitable contrivance to receive a strap by which the motion is to be conveyed to the machinery.

This wheel has a shaft fixed in the center and turns in the center of the frame on a metal step. On this shaft is a pinion about 6 inches diameter made of cast iron.

3. The Log Wheel is made of cast iron or any other suitable material about 6 feet diameter with a convenient number of logs. This log wheel turns on a shaft supported in the before mentioned rail and turning in a box in the upper part of the frame. The shaft is sufficiently high above the frame to admit of a cover.

Operation. The strap being passed round the strap wheel and continued a sufficient distance until the animal to pass over is caused over. The animal is attached to the strap connected with the shaft and is made to walk around the frame. This turns the cog wheel which operates on the pinion and causes the strap wheel to revolve. This motion is communicated to any kind of machinery by the rope or strap before mentioned. The frame here claimed, and which I desire to be secured by Letter Patent is the above described machine for conveying

Drawn

power to any kind of machinery. Further to illustrate my invention, I refer to the model and drawing of the same deposited in the Patent Office.

In testimony whereof I have hereunto signed my name before two witnesses and made out to the same this 16th day of November 1830.

York.

Disclaimer

I Joseph C. Country, Patentee of a Patent granted on the 14th day of December, 1830, for an improvement being "a Fodder Machine for conveying animal power to any kind of machinery" desire to be distinctly understood that I make no claim to the combination and arrangement of the frame, bog wheels, band or strap-wheel, shafts and sweep, as therein described.

All that I intend to claim and which I wish to secure by Letters Patent is the method of conveying power from the driving machine to any kind of machinery to be propelled, by means of a strap or band passing under the animal's foot from the band-wheel of the driving machine, to the machine to be propelled, in the manner before described, or in any other mode substantially the same in principle, where a belt, strap, cord, or chain is used. And I hereby disclaim all other rights or claims, secured or supposed to be secured by said Letters Patent except that which is now specially mentioned as claimed.

Washington, October 28, 1837.
